[57] CLAIM

The ornamental design for a remote controller for a television receiver, as shown and described.

DESCRIPTION

FIG. 1 is a perspective view of the bottom, front and right side of a remote controller for a television receiver showing our new design;

FIG. 2 is a front elevational view thereof;

FIG. 3 is a right side elevational view thereof;

FIG. 4 is a top plan view thereof;

FIG. 5 is a rear plan view thereof;

FIG. 6 is a left side elevational view thereof;

FIG. 7 is a bottom plan view thereof; and,

FIG. 8 is a perspective view similar to FIG. 1 with the cover in the open position.

The portion along the right side of the interior of the cover that is not visible in FIG. 8 is a mirror image of the left side of the interior of the cover.
